UNITED STATES PATENT OFFICE

AMY SHELDON, OF MIDDLETOWN, CONNECTICUT, ASSIGNOR TO THE RUSSELL MANUFACTURING COMPANY, OF MIDDLETOWN, CONNECTICUT, A CORPORATION OF CONNECTICUT

DESIGN FOR WEBBING FOR SUSPENDERS, GARTERS, AND SIMILAR ARTICLES

Application filed June 27, 1929. Serial No. 31,842. Term of patent 3½ years.

To all whom it may concern:

Be it known that I, AMY SHELDON, a citizen of the United States, and a resident of Middletown, in the county of Middlesex, and State of Connecticut, have invented a new, original, and ornamental Design for Webbing for Suspenders, Garters, and Similar Articles, of which the following is a specification, reference being had to the accompanying drawings, forming part thereof, in which the figure is a face view of a fabric embodying my invention.

I claim:—

The ornamental design for webbing for suspenders, garters and similar articles, as shown.

AMY SHELDON.
